DISPLAY RACK

Richard A. Klein, Boston, Mass., assignor to McCormick & Co., Incorporated, Baltimore, Md., a corporation of Maryland

Application July 19, 1948, Serial No. 39,443

6 Claims. (Cl. 211—181)

1

This invention is a novel improvement in display racks or the like for use in stores to display merchandise; and the principal object of the invention is to provide a simple, novel, and efficient rack consisting of a frame formed of rods or tubing, of metal or the like, adapted to support in superimposed relation, a plurality of shelves formed of expanded metal, which shelves are adjustable, supported at their ends, in the end members of the frame.

Other minor objects of the invention will be hereinafter set forth.

I will explain the invention with reference to the accompanying drawings, which illustrate one practical embodiment thereof, to enable others to adopt and use the same; and will summarize in the claims, the novel features of construction, and novel combinations of parts, for which protection is desired.

In said drawings:

Figure 1 is a front perspective view of the display rack.

Fig. 2 is a rear perspective view of the frame thereof, with the shelves removed.

Fig. 3 is a perspective view of one end of an expanded metal shelf.

Fig. 4 is a perspective view of a modified expanded metal shelf.

As shown, the frame of my novel display rack preferably comprises a pair of identical end members, formed of rods or tubes of metal or the like, each end member comprising a front rod 1, rounded rearwardly as at 1a at its upper end, and extending rearwardly as at 1b to form the top rod of the frame member, the inner end of top rod 1b being directed downwardly as at 1c, the rods 1 and 1c converging upwardly, and the rod 1 sloping upwardly and rearwardly, as shown. Between the rods 1 and 1c adjacent the top thereof are a plurality of cross rods 2 which are secured by welding or the like to the rods 1—1c, the same making a slight angle with the horizontal and sloping downwardly and rearwardly as shown.

The lower end of rod 1 is bent upwardly and rearwardly as at 1d and the lower end of rod 1c is bent upwardly and forwardly as at 1e, the upper ends of the portions 1d—1e being secured by welding or the like to the lower cross rod 2.

Extending downwardly from the upper rear

2

corner of each end member is a rod 3, disposed substantially parallel with the rod 1, same terminating at the lower cross rod 2 and being secured to the rods 1b and 2. Between the rods 1 and 3 are a series of shelf supports 4 secured to the said rods 1 and 3 by welding or the like, the same preferably being of relatively small diameter, and the supports 4 being substantially evenly spaced apart and disposed parallel with the cross rods 2.

Between the end members of the frame are horizontal bars 5 connecting the rods 3 of the respective end members, said bars 5 as shown in the drawing having their ends curled as at 5a around the said rods 3. Bars 5 are maintained in spaced relation by means of an inverted U-shaped member, the legs 6 of which are spaced apart a distance less than the lengths of the bars 5, the lower ends of the legs 6 terminating opposite the lower bar 5, and the top member 6a of the U-shaped member being disposed at substantially the height of the upper rear ends of the top rods 1b, as shown in Fig. 2. The legs 6 are secured by welding or the like to the respective bars 5. Cross members 7 are provided for the U-shaped member, secured to the lower bar 5 adjacent the lower ends of the legs 6 and to the remaining bars 5, the upper ends of the cross members 7 being secured to the top member 6a of the U-shaped member adjacent the upper corners thereof, the cross members 7 thereby imparting rigidity to the U-shaped member 6—6a to prevent racking thereof.

Below the top member 6a of the U-shaped member is a rod 8 having its ends secured to the legs 6 adjacent their upper end and also secured to the cross members 7, and inverted V-shaped members 9 are secured in horizontal spaced relation to the top member 6a and the rod 8. The frame, above described, forms a rigid structure in which the shelves may be placed and supported in different spaced vertical elevations or positions.

As shown in Figs. 1 and 3, the shelves 10 are preferably formed of sheets of expanded metal or the like, having closely spaced openings therein for the purpose of reducing weight, the ends of the shelves 10 being flanged downwardly as at 10a (Fig. 3), each shelf 10 being of length slightly greater than the spacing between the rods 2 and

4 of the said end members of the frame, the front and rear corners of the shelves 10 being recessed as at 10b and 10c (Fig. 3) so that the shelves may be passed between the rods 1 and 3 of the respective end members in order to rest upon the cross rods 2 or 4 of the end members of the frame.

The front of each shelf 10 is flanged downwardly and is covered by a solid strip 11 (Fig. 3) extending the full length of the shelf, each strip 11 being secured to the front of the downturned flange in any desired manner so as to conceal the same and to provide a flat base for the spaced undercut horizontal strips 12—13 (Fig. 3) at the top and bottom edge of each strip 11 which strips serve as a guide for a paper or other indicia strip (not shown) in the customary manner, the indicia strip being insertable between the guide strips 12—13 from the ends of the base 11.

The rear end of each shelf 10 is rounded upwardly as at 10d (Fig. 3) to rest against the legs 6 of the U-shaped member at the rear of the frame. In order to stiffen and form a finish for the outer ends of the flanges 10a and the sides and tops of the flanges 10d, the margins are preferably folded back upon themselves and welded together, as indicated at 10e. Thus, the shelves 10 form rigid unitary structures, and the same may be inserted in the frame so that their ends will rest upon any of the sets of cross rods 2 or 4 of the end members of the frame, the same ordinarily resting upon the cross rods 2, as indicated in Fig. 1.

The recesses 10b—10c in the corners of each shelf 10 are of sufficient depth to allow the shelves to be readily inserted and withdrawn from their respective positions in the frame members. For instance, in order to withdraw a shelf from the frame, one end must be raised to clear the cross rods 2 or 4 upon which the shelf rests, and the shelf then shifted toward the opposite frame to release the raised corner, whereupon the shelf may be removed by merely lifting the said opposite end of the shelf and withdrawing same from between the rods 1 and 3 of the said opposite end members.

The backs 10d of the shelves 10 preferably, but not necessarily, conform with the spacing between the cross rods 2 of the frame members, the back 10d of the lowermost shelf 10 filling the gap between the two lowermost cross bars 2, while the backs 10d of the remaining shelves 10, with the exception of the uppermost shelf, filling the gaps between their related cross rod 2. The uppermost shelf 10 is adapted to seat upon the upper cross bar 2 and its back 10d terminates substantially flush with the top rod 6a of the inverted U-shaped member of the frame.

Instead of using the shelf structure shown in Figs. 1 and 3, a modified structure may be used as shown in Fig. 4, the same being formed of expanded metal having its front edge turned down and covered by the solid strip 11 at the upper and lower edges of which are provided the horizontal strips 12 and 13. In this modification the entire end of each shelf is not flanged downwardly as in Fig. 3, but a central portion thereof is flanged downwardly as at 10x to serve the same purpose as the flange 10a, Fig. 3, thereby dispensing with the necessity of providing the recesses 10b and 10c as shown in Fig. 3.

By the above construction, a simple and efficient display rack is provided in which the shelves 10 are each adjustable with respect to vertical spacing by increments equal to the spacing between the cross rods 2 and 4 of the end

members. The articles to be displayed may be placed upon the shelves 10, and suitable indicia inserted between the guide strips 12 and 13 of the respective shelves and disposed opposite or in front of the related merchandise. The frame and shelves are easy to construct, require no extraneous fastenings such as bolts or screws to secure the parts together, and the rack will obviously be of rigid construction.

I do not limit my invention to the exact form shown in the drawings, for obviously changes may be made therein within the scope of the claims.

I claim:

1. In a display rack having a series of vertically spaced shelves, a frame comprising a back member and end members; each end member comprising substantially vertical front and rear rods converging upwardly and connected at their upper ends by a top rod, a series of spaced cross-rods sloping downwardly and rearwardly and connected with the said front and rear rods, an intermediate rod extending from the upper rear corner of the end frame to the lowermost cross-rod and disposed substantially parallel with the front rod and connected with the series of cross-rods, and a series of other cross rods disposed parallel with the first series and connected with the front rod and intermediate rod; said back member connecting said end members and maintaining same in spaced relation; and said shelves in the frame having their ends resting upon the said cross-rods.

2. In a rack as set forth in claim 1, said back member being of inverted U-shape and having a series of cross-bars connected to and extending beyond the legs of the U-shaped member, with their outer ends connected with the intermediate rods of the respective end members; and opposed diagonal bars connecting the top member of the U-shaped member adjacent the corners thereof and the said cross-bars respectively.

3. In a rack as set forth in claim 2, a bar disposed parallel with and below the top member of the U-shaped member with its ends secured to the said legs; and a series of spaced backing members connecting the said bar and top member.

4. In a rack, a frame having end members; each end member comprising substantially vertical front and rear rods converging upwardly and connected at their upper ends by a top rod, a series of spaced cross-rods sloping downwardly and rearwardly and connected with the said front and rear rods, an intermediate rod extending from the upper rear corner of the end frame to the lowermost cross-rod and disposed substantially parallel with the front rod and connected with the series of cross-rods, and a series of other cross rods disposed parallel with the first series and connected with the front rod and intermediate rod.

5. In a display rack, a frame having a back member and end members having intermediate upright bars supporting cross-bars; said back member connecting said end members and maintaining same in spaced relation; said back member being of inverted U-shape and having a series of cross-bars connected to and extending beyond the legs of the U-shaped member with their outer ends connected with the respective end members; and opposed diagonally disposed bars connecting the top member of the U-shaped member adjacent the corners thereof and the said cross-bars respectively.

6. In a rack as set forth in claim 5, a bar disposed parallel with and below the top member of the U-shaped member with its ends secured to the said legs; and a series of spaced backing members connecting the said bar and top member.
